UNITED STATES PATENT OFFICE.

MEYER L. ROBBINS, OF NEW YORK, N. Y., ASSIGNOR TO UNTERMEYER ROBBINS & CO.,
OF NEW YORK, N. Y., A CORPORATION OF NEW YORK.

DESIGN FOR A RING.

Application filed May 16, 1925. Serial No. 13,462. Term of patent 7 years.

To all whom it may concern:

Be it known that I, MEYER L. ROBBINS, a citizen of the United States of America, and a resident of the borough of Manhattan, city, county, and State of New York, have invented a new, original, and ornamental Design for a Ring, of which the following description, in connection with the accompanying drawing, is a specification.

Referring to the drawings:

Figure 1 is a top plan view of a ring containing a gem cluster; and

Figure 2 is a side elevation of the article shown in Figure 1 showing my new design.

I claim as my invention:

The ornamental design for a ring, as shown.

MEYER L. ROBBINS.
